UNITED STATES PATENT OFFICE.

ELAM I. ANDERSON, OF CHICAGO, ILLINOIS.

ROTARY EXPLOSIVE-ENGINE.

1,107,872.

Specification of Letters Patent. Patented Aug. 18, 1914.

Application filed August 26, 1913. Serial No. 786,775.

To all whom it may concern:

Be it known that I, ELAM I. ANDERSON, a citizen of the United States, residing at Chicago, in the county of Cook and State of Illinois, have invented certain new and useful Improvements in Rotary Explosive-Engines; and I do hereby declare the following to be a full, clear, and exact description of the invention, such as will enable others skilled in the art to which it appertains to make and use the same.

This invention relates to new and useful improvements in rotary explosive engines and has for its object the provision of a device of the above character which will combine the advantages of a rotary engine with those of the ordinary type of reciprocating engine.

Another object of my invention is the provision of such a device wherein the gases are compressed before being admitted to the explosion chamber, thereby increasing the amount of explosion caused by the firing of the gases.

A further object of my invention is the provision of such a device which will be positively operated thereby insuring a proper timing of each of the working parts and eliminating any lost motion.

A still further object of my invention is the provision of such a device in which the expense of manufacture will be materially lessened and the power developed materially increased.

With the above and other objects in view I now proceed to describe my invention in the following specification and accompanying drawings, in which,

Figure 1 is a side view in elevation of my improved rotary explosive engine, Fig. 2 is an end view in elevation of my improved rotary explosive engine, Fig. 3 is a transverse sectional view of my improved engine taken on line 3—3 of Fig. 2, Fig. 4 is a longitudinal sectional view of my improved engine taken on line 4—4 of Fig. 1, Fig. 5 is a detail view of the rocker arm used to operate the compressor, and Fig. 6 is a detail sectional view of the casing.

Referring to the drawings by characters of reference 1 indicates the casing of my im-

proved explosive engine, which is preferably rectangular in cross section and is adapted to form the annular chamber 2. This casing is preferably provided at its 55 lateral extremities with suitable bearings, in which the axle 3, having secured thereto the fly-wheel 4, is journaled. This axle 3 also carries at its end opposite the fly wheel a suitable spur gear 5, the use of which will 60 be more fully hereinafter described. Intermediate the ends of the axle 3 and rigidly secured thereto I also provide a rotor, indicated generally by the numeral 6. This rotor preferably comprises the hub 7 having 65 formed integrally therewith the radially extending spokes 8 to the outer ends of which is secured the rim 9 which is preferably recessed, as shown at 10, to form the pockets against which the explosion is adapted to 70 exert pressure.

The casing 1 is preferably provided with the inlet aperture 11 and the exhaust aperture 12. Suitably secured to the casing in registration with the exhaust aperture 1 75 preferably provide a suitable exhaust pipe 13 which is held thereto by means of the flange 14. This flange 14 is provided with apertures through which the shanks of the bolts 15 are adapted to extend.

A suitable cylinder 16 is provided at its lower end with the annular flange 17 which is curved to fit the contour of the casing, as clearly illustrated in Fig. 3. This cylinder 16 is also provided intermediate its ends 85 with a suitable inwardly extending annular flange 18 having formed therein the valve seat 19 with which the valve 20 is adapted to coöperate. A suitable inlet port 21 is formed in the side of the cylinder and is 90 adapted to be closed by means of the valve 22, which is adapted to admit the gas to the cylinder when the device is in operation.

A suitable piston 23 is slidably mounted in the cylinder and is adapted to be operated 95 by the piston rod 24 which is pivotally secured thereto, by means of the pin 25. The upper end of this piston rod is preferably provided with the annular groove 26 which is adapted to receive the end of the rocker 100 arm 27. This rocker arm is pivotally supported on the bracket 28 which is secured to

the side of the cylinder as clearly illustrated in Fig. 2. The end of the rocker arm 27, opposite the end which is connected to the piston, is preferably provided with a suitable aperture through which the operating rod is adapted to extend.

Pivotal secured to the casing at a point immediately adjacent the cylinder I preferably provide a flap valve 29 which is adapted 10 to form a closure for said cylinder and be intermittently opened when the engine is in operation. This flap valve is secured to the transversely extending axle 30 which is provided with an extension on which the arm 15 31 is adapted to be secured.

Secured to the casing and extending inwardly with relation thereto I preferably provide the brackets 32 on which are rotatably mounted the spur gears 33. These 20 spur gears 33 are adapted to mesh with the large spur gear 5 and be driven thereby. A suitable rod 34 is eccentrically secured to one of the gears 33 and is extended upwardly, as clearly shown, and through the 25 aperture in the rocker arm 27, thereby causing the rocker arm to reciprocate the piston 23, when the device is in operation. A rod similar to the rod 34, which is indicated by the numeral 35, is eccentrically mounted, at 30 36, to the opposite gear wheel 33 and its upper end is connected to the arm 31, as clearly illustrated by the numeral 37. Each of the rods 34 and 35 is carried in suitable bearings 38 which allow free movement of 35 said rod and permit the device to operate without any interference. A chamber 39 is formed in the wall of said casing and is adapted to permit the exploded gases to enter thereinto and thereby eliminate a 40 good deal of the noise due to the explosion of the gases in the cylinder of the motor. A suitable spark plug 40 is secured in the cylinder 16 at a point just below the wall which separates the compression chamber 45 from the explosion chamber. This plug is adapted to cause the compressed gases in the explosion chamber to be fired and thereby set the motor in operation.

It will be apparent from the foregoing 50 that when it is desired to make use of my improved engine the same is connected to a suitable source of gas supply and gas is admitted to the compression chamber at the instant that the piston is raised. The gas 55 is then forced downwardly and through the valve 18 into the explosion chamber, at which time, a contact is formed and the spark jumps between the points of the spark plug, thereby firing the gas and causing the 60 same to expand against the end of the recess 10 which is formed in the rotor. It will be obvious that the expansion of the gases

will cause the rotor to revolve around its axis and when the gas contained in the pocket of the rotor reaches the chamber 39 65 it again expands, thereby reducing the pressure and eliminating considerable of the noise, caused by the explosion. This operation is repeated four times in one revolution of the fly-wheel 4, thereby providing an 70 engine which will give the greatest amount of power at a minimum of expense.

While in the foregoing I have shown and described the preferred embodiment of my invention I wish it to be understood that I 75 may change the specific arrangement and combination of parts without in any way departing from the spirit and scope of my invention as defined in the appended claims.

What is claimed is:—

1. A device of the character described comprising a casing, said casing forming an annular chamber, a cylinder operatively connected with said casing, said cylinder being divided into compression and explosion chambers, a valve adapted to form a closure between said chambers, said valve being automatically operated by the compression of the gases in the compression chamber, means to admit gases to the compression chamber, a spark plug in the explosion chamber to cause the gases to explode, a flap valve interposed between the explosion chamber and the annular chamber, said flap valve being rigidly secured to the casing, a lever secured to the end of the flap valve, a rotor rotatably mounted on a shaft, a gear wheel secured to the end of said rotor shaft and adapted to revolve therewith, spur gears adapted to mesh with said gear wheel, a 100 rod eccentrically mounted on one of said spur gears and being connected at its upper extremity to the lever, a piston slidably mounted in the compression chamber of the cylinder, a rod connected to the other of 105 said spur gears, said rod being eccentrically mounted thereon, a bracket secured to the upper extremity of the cylinder, a rocker arm pivotally mounted in said bracket, one end of said rocker arm being connected to 110 the piston and the other end of said rocker arm being connected to the rod, whereby when the wheel is rotated the rod will slide and cause the piston to reciprocate in the cylinder, thereby compressing gases and 115 forcing said gases into the explosion chamber.

2. In combination with a rotary internal combustion engine comprising a casing forming an annular chamber, a rotor operatively mounted in said casing, and a compressing cylinder mounted on said casing, a gear wheel secured to the rotor and rotatable therewith, spur gears operatively 120

mounted with relation to the gear wheel, a flap valve adapted to close the opening between the compression chamber and the annular chamber, a rod eccentrically mounted 5 on one of the gear wheels and adapted to actuate the flap valve, a piston slideable in the compressing cylinder, and a rod eccentrically mounted on the other of the spur

gear wheels, and operatively connected with the piston, whereby the same is actuated. 10

In testimony whereof I affix my signature in presence of two witnesses.

ELAM I. ANDERSON.
